UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 26, 1923. Serial No. 670,818.

To all whom it may concern:

- Be it known that I, EDGAR H. CLARK, a citizen of the United States of America, residing at Richmond Hill, in the county of 5 Queens and State of New York, have invented certain new and useful Improvements in Telephone-Exchange Systems, of which the following is a full, clear, concise, and exact description.
- 10 This invention relates to telephone exchange systems and especially to systems of the character in which automatic switching apparatus is employed for establishing connections.
- 15 The object of this invention is to improve and simplify telephone systems of the type using coordinate selective switches by transmitting the switch operating impulses directly to said switches.
- 20 A feature of the invention relates to the provision of means whereby the impulses for setting the switches may be sent over the extended connection directly to the successive switches to selectively operate the 25 same.
- The several sheets of drawing have been arranged in the order illustrated in Fig. 6 and disclose a telephone exchange system employing switches of the coordinate type.
- 30 Fig. 1 shows diagrammatically a coordinate line switch in which the subscriber's lines terminate.
- Fig. 2 illustrates two separate first selector switches of the coordinate type in which appear trunks incoming from the line switches.
- 35 Fig. 3 shows certain controlling equipment associated with the first selector switches and the trunks outgoing therefrom.
- Fig. 4 shows one of the number of trunks 40 outgoing from the selector switch in Fig. 2 together with certain controlling equipment.
- Fig. 5 shows a coordinate connector switch for completing connections to subscribers' lines.
- 45 In the system shown, subscribers' lines, such as the lines 101 and 102 incoming to the central office, terminate in the line switches 100. Outgoing from these line switches are a number of trunks such as the 50 trunks 103 and 104 which lead to first group selector switches. Trunks 103 and 104 are shown as appearing in the vertical rows 201 and 202 respectively of the coordinate group selector switch 200. Other 55 trunks incoming from the same and other switches may terminate in the same group selector 200 or in other group selectors such as the selector 210. Two additional trunks 226 and 227 are shown terminating in the group selector switch 210.
- 60 Outgoing from the first group selector switches are a number of numerical groups of trunks. Each of these groups of trunks is multiplied so as to appear in a plurality of the first group selector switches 200, 210, etc., in order that access may be had through any of the several switches. The trunks are arranged on a numerical basis whereby each numerical group appears in a certain vertical row of contacts and in a certain portion 65 of the row in each of the several switches to which they are multiplied. Considering the selector switch 200, for instance, the total number of horizontal links 207, 208, 209, etc., are divided into two groups 205 and 206. 70 While the section 205 is shown as containing only two links 207 and 208 and the section 206 is represented by a single link 209, it will be understood that each section may contain a large number of these horizontal 75 links. Each vertical row 203 and 204, etc., is divided into two groups of trunks, namely, the group relating to the lower section of links 205 and the group relating to the upper section of links 206. All even numbered 80 groups of trunks appear in the lower section of the vertical rows while all odd numbered groups of trunks appear in the upper section of the vertical rows. For instance, the group of trunks 225, 224, etc., appearing in the lower section of the vertical row 203 is numerically identified by the digit 2, while the group of trunks in the upper half 85 of the vertical row 203 is identified by the digit 1, which is odd. Similarly, the group 90 of trunks 221, 222, etc., is identified by the digit 4 while the group of trunks 223, etc., in the upper row of the vertical row 204 is identified by the digit 3. A similar grouping and allotment of the trunks occur in 95 each of the other selector switches 210. It will be noted, for instance, that the trunk 224 which occurs in the row 203 accessible to the link 207 in the switch 200 is multiplied and occurs similarly in the switch 210 before the horizontal link 211. The same 100 holds true with respect to all other trunks.
- Each of the vertical rows of contacts 203, 204, etc., in the selector switch 200 is provided with an individual multi-contact relay 110

300, 301, 302, 303, etc. The purpose of these relays will be described hereinafter.

The trunks outgoing from the first selector switches in the present disclosure are 5 shown terminating in the vertical rows of contacts of connector switches such as the switch 500. The trunk 221 shown in full terminates in the vertical row of contacts 501 of the switch 500. A second trunk 523 10 is shown terminating in the vertical row of contacts 502.

The subscribers' lines also terminate in the connector switches of the vertical rows 503, 504, etc. The horizontal links of the switch 15 500 are divided into ten groups, 506, 507, 508, etc., each of which represents one of the tens digits. Furthermore, each of the vertical rows 503, 504, etc., represents one of the units digits. Accordingly, the line 515 appearing before the group of links 506 has 20 No. 1 for its tens digit and since it occurs in the vertical row 503, also has No. 1 for its units digit. The line 516 has the same tens digit No. 1, but since it occurs in the vertical 25 row 504 has the No. 2 for its units digit. Similarly, the line 517 is identified by the tens digit 1 and the units digit 3.

Each of the trunks leading from the line switch 100 to the first group selectors is provided with an individual stepping switch which serves to take the series of impulses directly from the dial and to determine the setting of the coordinate group selector switch accordingly. In Fig. 1, the stepping 35 switch 105 is related to the trunk 104, while the second stepping switch 109 may, for instance, be associated with the other trunk 103.

Referring to the trunk 221 which leads 40 from the first group selector to the connector switch 500, the stepping switches 400 and 401 shown in Fig. 4, are individual to this trunk and serve to receive the tens and units series of impulses for setting the connector switch 500. Each of the several trunks 45 appearing in the connector switches is provided with a similar equipment.

By means of these individual recording 50 switches associated with each of the trunks incoming to a selector switch, the switches may be set by means of the impulses transmitted directly thereto without the necessity of any common recording and controlling equipment located in the exchange. The coordinate switches employed in this system 55 comprise briefly, a plurality of vertical operating bars, one for each vertical row of contacts for preparing said contacts for operation. In addition, there is provided a plurality of horizontal operating bars, each 60 individual to one of the horizontal links for operating the contacts to establish connections between the incoming and outgoing lines by way of the horizontal links. These operating 65 bars are actuated by means of vertical

and horizontal operating magnets. For a more detailed explanation of the construction and operation of these switches, reference is made to the patent to C. L. Goodrum and J. N. Reynolds No. 1,515,735, granted November 18, 1924, and the patent to S. B. Williams, No. 1,517,331, granted December 2, 1924.

The details of the connection will now be 75 considered. When the calling subscriber of line 101 initiates a call his line is extended through the line switch 100 to an idle trunk such as the trunk 104. Immediately that the connection is extended through the line switch, line relay 116 operates in series with the calling line. Relay 116 operates a slow release relay 117. Relay 117 at its left contact applies ground potential to the test and holding conductor 124 of the trunk 104.

Assuming that the number of the wanted 85 line 517 is 413 the calling subscriber first transmits a series of four impulses. On the first opening of the line, relay 116 releases and closes an obvious circuit for operating slow release relay 118 and the stepping magnet 119. The magnet 119 operates and steps the brushes 107 and 108 of the register switch 105 one step forward. For each successive opening and closure of the line, the brushes 107 and 108 are advanced until they reach their 4th position contacts. After an interval has elapsed following the series of impulses, the slow relay 118 becomes deenergized and operates the relay 106 which is individual to the trunk 104. A circuit for 100 this purpose leads from battery, through the left winding of said relay, contact of relay 118, spring contacts 121 and 120 which are closed on the first step of the switch 105, common conductor 125, outer back contact 105 of relay 114, to ground at the contact of slow operating relay 113. Relay 106 operates and prepares a locking circuit for itself and an operating circuit for relay 114. This circuit leads from battery, through the right winding and contact of relay 106, inner right back contact of relay 110, winding of relay 114 to ground at the contact of relay 113.

Relay 106 closes an obvious circuit for the 110 cut-off 115. Relay 115 releases the line relay 116 which in turn opens the holding circuit of slow release relay 117. Before relay 117 can release to remove ground from the test conductor 124, another ground will be 115 substituted in its place in the manner to be described hereinafter. Relay 114 operates the vertical magnet 214 in a circuit from ground, through the contact of relay 113, outer front contact of relay 114, conductor 126, inner left contact of relay 106, winding of the magnet 214 to battery. Magnet 120 214 operates the bar associated with the vertical row of contacts in which appears the trunk 104, thus preparing these contacts 125 for operation. Relay 114 also operates the 130

vertical operating magnet 216 and the multi-contact relay 301 in a circuit from ground, through the contact of relay 113, inner contact of relay 114, outermost right armature of relay 106, brush 108 and its 4th position contact, conductor 127 and thence in parallel through the windings of the magnet 216 and the relay 301 to battery. Magnet 216 operates the bar associated with the vertical row of contacts 204 in the lower section of which appear the trunks of the group identified by the digit 4.

With the vertical magnets 214 and 216 operated jointly, an energizing circuit is completed for the common control relay 113. This circuit leads from ground, through the contact of magnet 216, contact of relay 214 and thence through the winding of relay 113 to battery. Due to the fact that the relay 113 is slow in operating it does not open its contacts until after sufficient time has expired for the operation of the selector switch 200 in the manner about to be discussed.

It will be assumed that the first trunk 221 in the chosen group is idle at this time. Consequently, when the test is made as will now be explained, the relay 306, which is individual to this trunk, will be found in a released condition. The testing circuit for associating the first idle trunk in the selected group may be traced from ground, through the contact of relay 113, inner contact of relay 114, middle right contact of relay 106, the brush 107 and its 4th position contact, conductor 228, spring contacts of the relay 301, conductor 310, innermost right back contact of relay 306, conductor 311, back contact of relay 219, left hand winding of the horizontal magnet 217 to battery. It will be noted that the circuit for the horizontal magnet 217 is closed at substantially the same time as the circuits for magnets 214 and 216. Magnet 217, however, being somewhat sluggish in operation does not actuate the bar 232 until after magnets 214 and 216 have operated. The magnet 217 which is individual to the link 207, before which appears the idle trunk 221, operates in the above traced circuit and rotates the associated bar 232 to effect connection between the incoming trunk 104 and the outgoing trunk 221. The instant the connection is effected the circuit is completed from battery through both windings of the horizontal magnet 217, winding of relay 219 and thence through the contacts of switch 200 to the grounded test conductor 124 of the trunk 104. The relay 219, however, does not operate in this circuit since it is already shunted by the circuit above traced. Moreover, when the switch is operated a circuit is completed for the trunk relay 306 which is traceable from battery, through the resistance 307, winding of said relay, conductor 312, contacts of the switch 200 to the grounded test

conductor 124. Relay 306, however, does not operate since it is shunted by the circuit from battery, through the resistance 307, left back contact of relay 306 directly to the grounded conductor 310.

The foregoing operations, including the selection and operation of the idle horizontal magnet 217, take place before the slow relay 113 has time to operate. As soon as said relay finally does operate, it removes ground from the holding circuits of relay 106, vertical magnets 214 and 216 and also the multi-contact relay 301. These relays and magnets thereupon release.

With the vertical operating magnets 214 and 216 released the connection established through the switch 200 is maintained by the continued energization of the horizontal operating magnet 217. This connection extends by way of the trunk 221 whereupon the line relay 415, shown in Fig. 4, is connected directly in series with the calling subscriber's line. Relay 415 operates the slow release 416 which applies ground potential to the holding conductor 312 of the trunk 221. Thus, ground is extended back over the test conductor to the conductor 124 of trunk 104 and the relay 115 is locked thereto through its inner left front contact. This locking circuit for relay 115 is completed before the relay 106 releases as above explained.

When relay 113 operates and 106 releases the shunt circuits around the windings of magnet 217, and relays 219 and 306 are removed and these relays operate in the circuits already traced for them. The magnet 217 and relay 219 are now held in a circuit from battery, through the windings of magnet 217, winding of relay 219, contacts of the switch 200 and test conductor 312 to ground at the left contact of relay 416.

Relay 306, in operating, identifies the trunk 221 as busy in order to prevent any other switch from attempting to select this trunk.

Since the register switch 105 is no longer needed, it is immediately restored to normal. The circuit for this purpose may be traced from battery, through the winding and interrupting contact of the magnet 119, spring contacts 122 and 123, outer left contact of relay 115 to ground at the outermost left contact of relay 106. The magnet 119 steps the switch back to its normal position where the off-normal contacts 120, 121, 122 and 123 are opened and the switch comes to rest.

Next, the calling subscriber transmits a single impulse representing the tens digit. Upon the opening of the line circuit the relay 415 releases and closes an obvious circuit for slow to release relay 418 and the stepping magnet 402 of the tens register switch 400. At the end of the line interruption, the magnet 402 releases and the

brush 403 is advanced to its first position contact. While relay 418 is operated, a circuit is closed from battery, through the winding of relay 420, inner left contact of relay 419, front contact of relay 418, outer left contact of relay 419 to ground. Relay 420 operates and prepares a circuit for itself and relay 419 as follows: battery, through the windings of said relays, contacts of relay 420 and conductor 423 to ground at the contact of relay 412. Relay 419, however, being shunted, does not operate at this time.

After an interval, relay 418 releases and removing the shunt permits relay 419 to operate.

Next, the subscriber transmits the units series of impulses consisting of three pulses. For each interruption of the line, relay 415 releases and a circuit is closed for the operation of the stepping magnet 404 of the register switch 401. This circuit leads from ground, through the back contact of relay 415, inner right contact of relay 416, right contact of relay 417, winding of relay 418, right front contact of relay 419, winding of magnet 404 to battery. After the switch 401 has been stepped to its 3rd position contact, relay 418 releases and causes the operation of relay 414. The circuit for this purpose may be traced from battery, through the left winding of relay 414, back contact of relay 418, outer left contact of relay 419, off-normal spring contacts 408 and 409 of the switch 401, outer left contact of relay 413 to ground at the contact of relay 412. Relay 414 operates and locks through its right winding and contact in a circuit which also causes the operation of relay 413. Relay 414, in operating, closes an obvious circuit for the relay 417 which operates and locks to the grounded conductor 312 of the trunk 221.

Relay 413 causes the operation of the vertical operating magnet 511 in a circuit from ground, through the contact of relay 412, inner contact of relay 413, inner left contact of relay 414, and winding of magnet 511 to battery. Magnet 511 operates the associated bar and prepares the contacts in the row 501 in which appears the trunk 221. Since the units register switch 401 is standing in its 3rd position, the relay 413, in operating, causes the operation of the vertical magnet 514 which controls the row of contacts 505, in which appear lines having the units designation 3. The circuit for this purpose leads from ground, through the outer front contact of relay 413, outer right contact of relay 414, brush 405 in position 3, winding of the magnet 514 to battery.

The joint operation of the magnets 511 and 514 closes a circuit for the slow operating relay 412 which is obvious from inspection. Relay 412 requires an interval to operate during which time the connection is

established through the switch 500 as will be described presently. The joint operation of the magnets 511 and 514 also results in the extension of the starter wire to the group of horizontal links 506 which have access to the desired subscriber's line 517. This circuit may be traced from ground, through the contacts of magnets 514 and 511 thence over conductor 425, brush 403 and its first position contact, conductor 426, front contact of relay 520 (assuming the link 509 to be busy), back contact of relay 521 (assuming the link 510 to be idle), left hand winding of the horizontal operating magnet 519 to battery. Magnet 519 operates the associated bar 525 and effects a connection through the switch 500 whereby the trunk 221 is connected over link 510 to the subscriber's line 517. Immediately when the connection is established a circuit is completed from battery through the windings of magnet 519, winding of relay 521, through contacts of the switch 500 to the test conductor 524 of the trunk 221 to ground at the outer right contact of the relay 416. Relay 521, however, does not operate at this time.

After an interval, relay 412 attracts its armature and causes the release of relays 413, 414, 419 and 420. With these relays released, the shunt is removed from around relay 521 and this relay operates in series with the winding of magnet 519. Relay 412 also causes the release of the vertical magnets 511 and 514 whereby the connection from the switch 500 is maintained by the continued energization of the horizontal magnet 519.

Since the register switches 400 and 401 are no longer required for this connection they are restored to their normal positions. The circuit for restoring switch 400 may be traced from battery, through the winding and contact of magnet 402, off-normal contacts 406 and 407, conductor 427, outer left contact of relay 417 to ground at the left back contact of relay 414. The circuit for restoring switch 401 extends from battery, through the winding and contact of magnet 404 and off-normal contacts 410 and 411 to the grounded conductor 427. When the switches have reached their normal positions, their off-normal contacts are opened and the switches come to rest.

In any manner well known in the art, current may be applied to the called subscriber's line 517 to inform him that a calling party is waiting. When the called subscriber removes his receiver from the switchhook, talking current is supplied to this line through the windings of relay 421.

After conversation has been completed, the subscribers replace their receivers on the switchhooks. When the calling subscriber hangs up his receiver, the relay 415 releases and thereby releases the relay 416. Relay

416, in turn, releases the relay 417. The release of these relays removes ground potential from the conductor 312 whereby the connection through the switch 200 is disestablished. The called subscriber in replacing his receiver opens the circuit of relay 421 which removes ground potential from the conductor 524, causing the release of the horizontal magnet 519 and the consequent disestablishment of the connection through the connector switch 500.

In case the first digit of the wanted number is odd, the selection takes place through the upper section 206 of the switch 200. If the digit is 3, for instance, the group of trunks occurs in the upper part of the row 204, one of these trunks 223 being illustrated. The digit being three, the register switch 105 stands on its 3rd position contact and the testing circuit for the horizontal magnets may be traced as follows: ground, through contact of relay 113, inner contact of relay 114, middle right contact of relay 106, brush 107 in position 3, conductor 229, contacts of the relay 301, inner right back contact of trunk relay 313 (assuming the trunk 223 and the associated link 209 to be idle) right back contact of relay 230, left winding of horizontal magnet 231 to battery. In the manner fully described hereinbefore the horizontal magnet 231 effects connection through the switch 200 over the link 209 to the idle trunk 223.

Should the incoming call be extended over one of the trunks 226, 227 leading into the second selector switch 210, operations take place in the same manner as hereinbefore described and the connection is extended over an idle trunk to a connector switch.

The invention claimed is:

1. In a telephone system, a selective switch comprising a number of rows each including a plurality of separately operable sets of contacts, switching bars, one for each row, a line extending to said switch and appearing in the contacts thereof, and means individual to the line and responsive to impulses sent thereover directly to the switch for causing the operation of said bars to selectively extend the line through said switch.

2. In a telephone system, a selective switch comprising a number of rows each including a plurality of separately operable

sets of contacts, switching bars, one for each row, a plurality of incoming lines appearing in the contacts of said switch, and means individual to each line and responsive to impulses sent thereover directly to the switch for causing the operation of said bars to selectively extend the line through said switch.

3. In a telephone system, a selective switch comprising a number of rows each including a plurality of separately operable sets of contacts, switching bars, one for each of said rows, other bars intersecting said first-mentioned bars and arranged for co-operation therewith, a telephone line extending to and appearing in contacts of said switch, and means associated with said line and responsive to impulses sent over the line directly to said switch for causing the operation of said bars to selectively extend the line through the switch.

4. In a telephone system, a selective switch comprising a number of rows each having a plurality of separately operable contact sets, links arranged in coordinate relation with said rows of contacts, switching bars, one for each row and one for each link, a line extending to said switch and appearing in the contacts thereof, and means associated with the line and responsive to impulses sent thereover directly to the switch for causing the cooperation of said bars to selectively extend the line through the switch.

5. In a telephone system, a selective switch having a number of rows each including a plurality of separately operable switch contacts, a plurality of links arranged in coordinate relation to said rows, incoming lines appearing in certain of said rows, numerical groups of outgoing lines appearing in other of said rows, switching bars, one for each row and one for each link, and means responsive to impulses sent directly over one of said incoming lines to the switch for causing the cooperation of said bars to extend the incoming line through one of said links to an outgoing line in a desired numerical group.

In witness whereof, I hereunto subscribe my name this 24th day of October, A. D. 1923.

EDGAR H. CLARK.
